Primary Examiner — Mary Ann Calabrese(74) *Attorney, Agent, or Firm* — Loeb & Loeb LLP**CLAIM**

The ornamental design for electric kettle, as shown and described.

DESCRIPTION

FIG. 1 is a Top view;

FIG. 2 is a Right view;

FIG. 3 is a Back view;

FIG. 4 is a Front view;

FIG. 5 is a Left view;

FIG. 6 is a Bottom view; and,

FIG. 7 is a Perspective view.

The portions of the electric kettle shown by coloring form no part of the claimed design.

1 Claim, 7 Drawing Sheets---
